PYROPHORIC POCKET LIGHTER

Filed Jan. 3, 1930

UNITED STATES PATENT OFFICE

EDWARD F. CLARK, OF RANGELEY, MAINE, AND JAMES F. ROGERS, OF NORTH ATTLEBORO, MASSACHUSETTS, ASSIGNEES, BY MESNE ASSIGNMENTS, TO ART METAL WORKS, INC., OF NEWARK, NEW JERSEY, A CORPORATION OF NEW JERSEY

PYROPHORIC POCKET LIGHTER

Application filed January 3, 1930. Serial No. 418,186.

This invention relates in general to improvements in pocket lighters of the pyrophoric type.

One of the objects of this invention is the provision of a pocket lighter involving the principles of construction whereby efficiency of operation and simplicity of construction are assured.

Another object of this invention is the provision in a pocket lighter of this type of a structure which requires but a single motion to uncover the wick and create sparks to ignite the vapors given off by the wick.

A further object of this invention is the provision in a lighter of this type of a construction by means of which the snuffer is automatically returned to cover up the wick when the pressure thereon is relieved.

A still further object of this invention is the provision of a snuffer arm construction operatively associated with a flint wheel so that upon movement of the snuffer arm to uncover the wick the flint wheel operates to produce a spark from the pyrophoric material and in the reverse movement of the snuffer arm to cover the wick, the flint wheel is not revolved.

These and other objects, as will appear from the following disclosures, are secured by means of this invention.

This invention resides substantially in the combination, construction, arrangement and relative location of parts, all as will be described in greater detail below.

35 Referring to the drawing—

Figure 1 is a vertical cross sectional view through the lighter of this invention;

40 Fig. 2 is a cross sectional view of the upper part of the lighter taken on the line 2—2 of Fig. 1;

Fig. 3 is a cross sectional view taken on the line 3—3 of Fig. 2;

45 Fig. 4 is an elevational view of the upper part of the lighter showing the relation of the ratchet wheels, flint wheel, and snuffer arm;

50 Fig. 5 is an enlarged side elevational view showing the position of the snuffer arm with respect to its supports when pressure is applied thereto and it begins to rise;

Fig. 6 is a perspective view of the central spindle on which the movable parts are mounted and the spring support therein.

The construction comprising this invention and its operation will best be understood by reference to the drawing in detail. At 1 is shown the container for holding the absorbent material 7 and the volatile fuel commonly used in such lighter. This casing is provided with a threaded opening to receive the plug 2 through which the fuel is introduced to the interior of the container. The top of the container is shown at 4 and below it is the upper wall or partition 3 of the container 1. The top wall 4 is cut out at the center to provide a cavity below the upper end wall of the casing. The casing is provided with a wick tube 5 through which the wick 6 of the usual type projects. Extending upwardly through the container 1 is the tube 8 which is closed by means of an adjustable threaded plug 9. Extending from the upper end of the tube 8 is the pyrophoric material 11 which is urged upwardly by a spring 10 which lies between it and the adjustable plug 9. Mounted on the top of wall 4 are two brackets 12 in which is mounted the hollow central spindle 13. A small pin 14 extends through the tube 13 and is peened over at the ends to hold the parts in operative relation. Encircling the pin 14 is a spring 15 which has one end secured in a notch in the end of the tube 13 as shown at 15a in Fig. 6. The tube 13 is cut away, as shown at 13a for a short distance and the other end 15b of the spring extends therethrough.

Mounted on the tube 13 for rotation is the usual flint wheel 17. Also mounted on the tube 13 for rotation thereon is a cap member 18 which covers all the parts and comprises what might be called the snuffer arm. Mounted within this cap 18 is the snuffer member 29 which fits down over the wick to put out the flame and prevent evaporation of fuel when the device is not in use. At the point where the tube extends through the cap 18 on each side the hole is enlarged vertically into the slot, as shown at 16. The end 15b of the spring contacts with the lower rear edge formed in the cap 18 by cutting away a por-

100

tion thereof, as is clear in Figs. 1, 3 and 4. The spring thus urges the cap down into normally closed position, as shown in Figs. 1 and 3, so that the snuffer member 29 fits over the wick tube. The spring also acts to hold the cap upwardly, that is so that the lower end of slot 16 comes to the bottom of the tube 13. Also mounted on the tube 13 and secured in any suitable manner to the flint wheel and on each side thereof are the ratchet wheels 19. Thus the ratchet wheels and flint wheel rotate as a unit on the flint tube 13. As clearly shown in the drawing the cap 18 has formed on the interior thereof and in line with the ratchet wheels two pins 20.

In the normal position of the parts the snuffer arm 18 as described is in the position shown in Figs. 1 and 3 with the snuffer member 29 contacting with the wick tube 5 and the cap 18 held upwardly by the spring 15, as shown. In operating the lighter, pressure is first applied to the top of cap 18 and as a result it moves downwardly, in the position shown in Fig. 5 for example, so that the top 25 of the tube 13 contacts with the top end of slot 16. In other words, the cap 18 has a sliding vertical movement by reason of the slots 16 on the tube 13 and the first pressure thereon forces the cap downwardly. This 30 downward movement of the cap causes the pins 20 to move into engagement with the ratchets 19, as is clear for example in Fig. 5. Backward pressure is then imparted to the cap 18 causing it to rotate in a clockwise direction, as indicated in Fig. 5, and carrying 35 with it ratchet wheels 19 and flint wheel 17. As the flint wheel 17 moves across the top of the pyrophoric material 11 sparks are produced which are thrown against the end of wick 6 causing the vapors given off thereby 40 to be lighted. Hence with a single movement of the thumb the cap and snuffer, which together comprise the snuffer arm, move upwardly exposing the wick and at the same 45 time the flint wheel is rotated to produce sparks to ignite the vapor. During the movement of cap 18 spring 15 is put under tension so that when the cap is relieved of pressure the spring throws it back into closed position, as shown for example in Fig. 1. At 50 the beginning of this return movement of the cap the first thing that happens is that the spring throws the cap upwardly on the tube 13 and then the cap is given rotary motion 55 in a counter-clockwise direction to close it and snuff out the flame.

From the above description it will be apparent that we have devised an exceedingly simple structure in a pocket cigar and cigarette lighter in which the entire operation of exposing the wick, producing sparks, and igniting the vapor is all carried out with a single operation, namely effecting the movement of the cap, as has been described. It 60 will be apparent, of course, that we have

embodied certain principles of construction and operation in one physical form as set forth in the drawing for the purpose of illustrating these principles but we do not desire to be strictly limited to the physical 70 form depicted but to any mechanical structure within these principles as defined in the appended claims.

What we seek to secure by United States Letters Patent is:

1. In a pyrophoric lighter of the type described, the combination comprising a fuel container, a flint tube and wick tube mounted therein, a rotatably supported flint wheel on said container adapted to contact with 80 the flint which projects from the flint tube, a rotatable and vertically movable cap supported on the container, and means on said cap for effecting rotation of the flint wheel, said means on the cap moving into position 85 to engage and rotate the flint wheel when the cap is given a vertical and rotational movement.

2. In a pyrophoric lighter of the type described, the combination comprising a fuel 90 container, a flint tube having a flint therein mounted in the container, a wick tube mounted in said container, a flint wheel and ratchet wheels rotatably supported on the container for conjoint rotation, a slotted 95 snuffer arm supported at its slotted portion for rotation on and translation with respect to the container, and means on the snuffer arm for intermittently engaging the ratchet wheels to rotate the flint wheel as the snuffer 100 arm is moved.

3. In a pyrophoric lighter of the type described, the combination comprising a fuel container, a flint tube having a flint therein mounted in the container, a wick tube 105 mounted in said container, a flint wheel and ratchet wheels rotatably supported on the container for conjoint rotation, a snuffer arm mounted for rotational and vertical movement on said container, and means on said 110 snuffer arm for engaging the ratchet wheels upon vertical movement of the snuffer arm, said means effecting rotation of the ratchet wheels and flint wheel upon rotational movement of the snuffer arm.

4. In a pyrophoric lighter of the type described, the combination comprising a fuel container, a flint tube having a flint therein mounted in the container, a wick tube mounted in said container, a flint wheel supported on said container and ratchet wheels rotatably supported on either side of said flint wheel for conjoint rotation, a snuffer arm mounted for rotational and vertical movement on said container, and means on said snuffer arm for engaging the ratchet wheels upon vertical movement of the snuffer arm, said means effecting rotation of the ratchet wheels and flint wheel upon rotational movement of the snuffer arm, said snuffer arm be- 125

ing in the form of a cap which entirely encloses in one position the wick tube and wick and the flint wheel and ratchet wheels.

5. In a pyrophoric lighter of the type described, the combination comprising a fuel container, a flint tube having a flint therein mounted in the container, a wick tube mounted in said container, a flint wheel and ratchet wheels rotatably supported on the container for conjoint rotation, a snuffer arm mounted for rotation and vertical movement on said container, means on said snuffer arm for engaging the ratchet wheels upon vertical movement of the snuffer arm, said means effecting rotation of the ratchet wheels and flint wheel upon rotational movement of the snuffer arm, and means for resiliently resisting vertical and rotational movement of the snuffer arm and to effect closing movement thereof when relieved of pressure.

6. In a pyrophoric lighter of the type described, the combination comprising a fuel container having a flint tube and wick tube therein, a flint in said flint tube, a flint wheel 25 rotatably supported atop said container in working proximity with said flint, ratchet wheels secured to said flint wheel and adapted to rotation therewith, a slotted rotatable and vertically movable snuffer arm supported 30 on said container at its slotted portion for rotation with said flint and ratchet wheels on and at their common pivot, and means on said snuffer arm to interengage with the ratchet wheels upon depression of the snuff- 35 er arm.

7. In a pyrophoric lighter of the type described, the combination comprising a fuel container having a flint tube and a wick tube therein, a wick in said wick tube and a flint 40 in said flint tube, a snuffer cap for said wick tube, a plurality of brackets mounted atop said container, a hollowed out spindle mounted in said brackets, a pin extending through said hollowed out spindle having peened ends, a resilient element mounted on said pin within said hollow spindle and having an end thereof extending without said spindle, a rotatably supported flint wheel 45 mounted atop said container in working proximity with the flint, a ratchet wheel secured to said flint wheel for rotation therewith, a slotted rotatable and vertically movable snuffer arm adapted to carry said snuffer cap and supported on said container at its slotted portion and having a cutaway portion against which the end of the resilient element extending without the hollow spindle bears to normally keep the snuffer cap on the wick and 50 the snuffer arm out of engagement with the ratchet wheel, and means on said snuffer arm for effecting interengagement thereof with the ratchet wheels upon depression of the snuffer arm when the effect of the resilient element is overcome.

8. In a structure of the type described, a flint tube having a flint therein, a flint cutting wheel adapted to work against said flint, a hollowed out spindle shaft on which said flint cutting wheel may rotate, a ratchet 70 wheel secured to said flint cutting wheel for rotation therewith, a slotted snuffer arm secured at its slotted portion to said hollowed out spindle shaft and having a cutaway portion at one end thereof, a resilient member 75 disposed in said hollowed out spindle shaft and having an end thereof adapted to bear against the cutaway portion of the snuffer arm internally thereof to normally keep the snuffer arm in snuffing position and out of engagement with the ratchet wheel, and means for effecting interengagement thereof upon depression of the snuffer arm on the hollowed out spindle shaft at the slotted portion of said snuffer arm, when the effect of 80 the resilient member is overcome.

9. In a pyrophoric lighter of the type described, the combination comprising a fuel container, a wick tube and a wick supported 90 therein, a flint and a flint tube supported therein, a flint wheel rotatably supported in contact with the flint, a ratchet wheel secured to said flint wheel for conjoint rotation therewith, and a slotted cap adapted to translation at and along its slotted portion to engage 95 with and rotate said ratchet wheel to effect ignition of the wick when uncovered by actuation of the cap, said cap being adapted when no longer actuated to automatically disengage 100 from the ratchet wheel and be freely returned without rotation of the flint or ratchet wheels.

10. In a pyrophoric lighter of the type described, the combination comprising a fuel container, a flint tube supported therein, a flint in said tube, a wick tube, an inflammable wick in said wick tube, a pivot, a flint wheel 105 rotatably mounted on said pivot in contact with said flint, a ratchet wheel secured to said flint wheel for conjoint rotation therewith, a slotted translatable and rotatable cap 110 engaging at its slotted portion with the pivot of the ratchet and flint wheels, and means carried by said cap for effecting interengagement thereof with the ratchet wheel when said cap is depressed for subsequent rotation. 115

11. In a cigar lighter of the type described, a fuel container, a spark producing mechanism mounted atop said container, an inflammable wick, a snuffer cap, a slotted translatable and rotatable snuffer arm for carrying said cap, means normally tending to keep said snuffer arm disengaged from the spark producing mechanism, and means for effecting rotational interengagement between said snuffer arm and said spark producing mechanism after said snuffer arm has been translated and depressed for subsequent rotation. 120

12. In an arrangement of the type described, the combination comprising a flint tube having a resiliently mounted flint there- 125

in, a flint wheel rotatably supported so as to contact with the flint, a snuffer arm supported for rotation and translation, means for effecting interengagement of the snuffer arm with the flint wheel to rotate said wheel when pressure applied to the snuffer arm has caused it to translate into position for rotation, and means tending to effect disengagement thereof when the actuating pressure has been removed after rotation.

10 In testimony whereof we have hereunto set our hands on this 28th day of December, A. D. 1929.
